UNITED STATES PATENT OFFICE.

DON A. CLARK AND CLYDE E. LOWE, OF CLEVELAND, OHIO, ASSIGNEES TO THE CLYDE E. LOWE COMPANY, OF CLEVELAND, OHIO, A CORPORATION OF OHIO.

TIRE-CORE.

1,303,256.

Specification of Letters Patent. Patented May 13, 1919.

Application filed August 7, 1918. Serial No. 248,677.

To all whom it may concern:

Be it known that we, DON A. CLARK and CLYDE E. LOWE, citizens of the United States, residing at Cleveland, in the county of Cuyahoga and State of Ohio, have invented a certain new and useful Improvement in Tire-Cores, of which the following is a full, clear, and exact description, reference being had to the accompanying drawings.

10 This invention relates to cores for use in the manufacture of pneumatic tires and has especial reference to sheet metal cores of the general type described in and claimed in our Patent No. 1,273,032 granted July 16, 15 1918, and consisting essentially of a plurality of arcuate, hollow, sheet-metal sections secured around the periphery of a rigid metal ring. The objects of the present invention are the provision of new and simplified 20 means for securing the sheet metal bodies to said ring; for preventing the ingress of steam, water, or other objectionable fluids to the interior of the core; for securing together the various sections of the core in 25 case the same be of the collapsible type; for stiffening and strengthening the core; while further objects and advantages of our invention will become apparent as the description proceeds.

30 In the drawings accompanying and forming a part of this application we have shown a few of the many mechanical construction in which our inventive idea can be embodied, although this drawing is illustrative only and 35 is not intended to limit us to the constructions therein set forth. In this drawing, Figure 1 is a plan view of part of a collapsible tire core constructed in accordance with our invention; Fig. 2 is a cross sectional view 40 of the core shown in Fig. 1; Fig. 3 is a cross sectional view of a modified form of attachment shown in connection with the base ring of an integral core; Figs. 4, 5, and 6 illustrate modified modes of attaching the sheet 45 metal walls in connection with a different type of mounting sometimes employed with sectional cores; and Fig. 7 is a plan view of a part of the core shown in Fig. 6.

The essence of the present invention consists in this, that the sheet metal bodies are 50 formed at their inner parts with spaced integral flanges between which is inserted a flat sided supporting ring, said flanges being clamped thereto by fastening members arranged perpendicular to the plane of said

ring, and leakage into the core interior being prevented, if desired, by suitable packing material interposed between the ring and flanges, which material may be either metallic or non-metallic, bolted or rigid.

60

Describing the parts by reference characters, 1, 1, represent the body members of the tire core which in each case are formed of sheet metal, preferably by the process described and claimed in our application filed June 26, 1918, Serial No. 242,019. Each of said bodies is formed at the portion of smallest diameter with a pair of spaced inwardly projecting flanges 2-2, which are preferably substantially parallel. These 70 bodies are of arcuate shape and are assembled together end to end forming a complete circle, the various sections being preferably not less than 60° in extent nor greater than 180°. The ends of these sections are joined together in any suitable manner as by bracing sleeves (shown in dotted lines in Fig. 1) and their joints are shown at 3-3 in Fig. 1.

75

In the construction shown in Figs. 1 and 80 2, these sections are assembled around a rigid supporting ring 4, said ring having a flat-sided peripheral portion 5 introduced between the flanges 2-2, and having at each side an inclined face 6 bounding said flat-sided portion. The portion 5 is formed at spaced intervals with transverse threaded apertures 7, 7 in which are received the flat-headed screws 8-8, countersunk into the flanges 2-2 and serving to grip the parts 85 together. The margins of the flanges 2-2 are formed with laterally turned lips 9-9 which lie against the face 6-6. The ring is also shown as formed with grooves 10-10 receiving packing material by means of 90 95 which the ingress of fluid is prevented.

The core body 1 and ring 4 are severed at certain points by transverse scarf's 12-12 arranged at oblique angles to the radius so as to permit certain sections of the core to be 100 removed and the remainder of the same to be collapsed; and in order to secure said sections rigidly together we have shown a pair of rigid rings 13-13, each having upon one side an annular groove 14, one face of which, 105 as 15, is inclined complementarily to the wall 6, and the other, as 16, is fashioned to engage the shoulder 17 formed at the inside of the ring 4. The rings 13-13 being drawn toward each other by any suitable 110

means such as bolts or clamps (not shown) it will be clear that the core sections will be held rigidly together; and in the present instance we have shown the wall 15 as 5 overlying the lips 9-9 of the sheet metal body whereby the same are held in place with added firmness. The inner periphery of the ring 4 is shown as formed with a groove or recess 18 adapted for the reception 10 of the clutch or mandrel on which the core is mounted for operation.

In the modified construction shown in Fig. 3, the ring 4^a is made in a single piece, thus producing an integral or non-collapsible core such as is frequently used for small-sized tires or soft-bead tires. This ring, like the preceding is formed with a peripheral rectangular portion 5^a introduced between the flanges 2-2, and with a wall 6^a at the 15 base of such flat-sided part. Each side wall of the body 1 is formed at a point outside the flange 2 with an inward offset 20, while the inner margin of each flange 2 is formed with a laterally turned lip 9^a adapted to engage 20 the wall 6^a. Between each lip 9^a and the corresponding offset 20 there is interposed a sheet metal ring 21, whose inner part is flat to engage the corresponding flange 2, and whose outer part is flared to 25 correspond with the slope of the core wall. The thickness of this ring is the same as that of the offset 20, thereby forming a smooth-sided core. This ring and the flange therebeneath is traversed by a plurality of spaced 30 apertures receiving suitable fastening means such as the transverse rivets 22 whereby the parts are held together. The advantage of this construction is that the ring 21 distributes the pressure of the rivets, and also 35 forms a support or anvil for the operation of the cutting knife which is ordinarily applied in the angle between the flange and core-wall. The sides of the portion 5^a are shown as grooved at 10^a-10^a for the reception 40 of the packing material.

Referring now to the construction shown in Fig. 4, the ring 4^b is of the segmental type, and is formed at its inner part with a laterally facing annular groove, 25, receiving 45 the annular rib 26, of a continuous base-ring 27 by means of which the segments are secured together. The ring 27 is formed with a flange portion 28 overlying the interior of the ring 4^b and formed with a 50 groove or recess 18 for the reception of the clutch or mandrel. The rib 26 is provided with spaced lateral bolts 29 adapted to enter suitable apertures in the base of the groove 26 and to be held therein by nuts 30.

60 The peripheral portion of the ring 4^b is formed with a flat-sided part 5^b defined by the walls or shoulders 6^b. In the present instance these walls or shoulders lie inside of the plane of the ring sides, forming grooves, 65 whereas in the former embodiments they lay

outside, forming ribs; and the margins of the flanges 2-2 being laterally turned to form lips engaging these shoulders are in the present instance turned inwardly as at 9^b where previously they were turned outwardly. Suitable securing devices 8^b traverse the ring portions 5^b and engage the flanges 2-2, these devices in the present embodiment being represented by a rivet having flattened heads engaging countersunk 75 recesses in the flanges 2-2.

In the embodiment shown in Fig. 5 the ring and its adjuncts are the same as in Fig. 4 excepting that the side walls of the portions, 5^b, instead of being entirely smooth, 80 are countersunk at intervals as shown at 32, and the flanges 2-2 are embossed inwardly to fit these countersunk portions. This embossing forms upon the exterior of each flange the equivalent of a countersunk hole 85 for receiving the heads 33 of the fastenings, here shown as screws threaded into the ring. The advantage of this over that shown in Fig. 4 is that it provides a larger surface of contact between the fastenings and 90 flanges.

In the embodiment shown in Fig. 6 the ring and its adjuncts are the same as those shown in Figs. 4 and 5 except that the sides of the portions 5^b are formed with annular 95 grooves 35 and the flanges 2-2 are embossed inwardly to form annular embossed ribs 36 complementary to these grooves.

In the outer side of the channels defined by this embossing are located the washers 37 100 traversed by the fasteners 38 which may be either rivets or screws.

In the embodiments shown in Figs. 4, 5, and 6 the walls of the rings 4^a and 27 are preferably made flush with the exterior surfaces of the flanges 2-2; and the grooves receiving the lips 9^b are preferably sweated full of a fusible metal such as soft solder in order to inhibit the entrance of fluids. It will be understood that in the practical use 105 of the devices, either in the wrapping of the fabrics thereon or in the curing process in the mold, the operating pressure is inward, thus bringing a minimum of strain upon the fastenings and tending to force the flanges 110 into tighter contact with the ring (whether or not additional packing be employed) thus again tending to inhibit leakage. It will be understood that numerous changes in construction could be made without departing 115 from our inventive idea, and all such variations we desire to protect and secure in these Letters Patent.

Having thus described our invention, what we claim is:—

1. A tire core comprising, in combination, 125 a plurality of hollow arcuate sheet metal bodies arranged around a rigid metal ring, each body having a pair of inwardly projecting spaced flanges and said ring having a 130

peripheral portion projecting between said flanges, and means including laterally extending holding devices for clamping said flanges laterally against said ring.

5 2. In a tire core, a hollow arcuate sheet metal body having a pair of inwardly projecting spaced flanges, a ring having a portion located between said flanges, and means including headed fasteners for clamping said flanges against said ring, said fasteners being arranged with their length transverse to the plane of said ring.

10 3. In a tire core, a hollow arcuate sheet metal body having a pair of inwardly projecting spaced flanges, a ring having a portion located between said flanges, and headed securing devices traversing said flanges and affixed to said ring, the heads of said devices overlying said flanges.

15 4. In a tire core, a hollow arcuate sheet metal body having a pair of inwardly projecting spaced flanges, a ring having a portion located between said flanges, means for securing said flanges to said ring, and means preventing ingress of fluid between said flanges and ring.

20 5. In a tire core, a hollow arcuate sheet metal body having a pair of inwardly projecting spaced flanges, a ring having a portion located between said flanges, the sides of said ring being grooved, sealing material in said grooves, and means clamping said flanges against said ring.

25 6. In a tire core, a hollow arcuate sheet

metal body having a pair of inwardly projecting spaced flanges, a ring having a peripheral portion located between said flanges and having at each side a shoulder adjacent to said peripheral portion, said flanges having laterally turned lips adapted to rest against said shoulders, and means for clamping said flanges against said rings.

30 7. In a tire core, a hollow arcuate sheet metal body having a pair of inwardly projecting spaced flanges, each formed with a laterally-turned marginal lip, a ring having a peripheral portion located between said flanges, and a shoulder at each side engaging the corresponding lip, said ring being grooved for the reception of sealing material, and means for clamping said flanges to said ring.

35 8. In a tire core, a hollow arcuate sheet metal body having a pair of inwardly spaced flanges whose margins are formed with outwardly turned lips, a ring having a peripheral portion located between said flanges and a shoulder at each side engaging the corresponding lip, a clamping ring at each side of said first ring engaging the face of the corresponding lip opposite to its shoulder, and means for drawing said last rings together.

40 In testimony whereof, we hereunto affix our signatures.

DON A. CLARK.
CLYDE E. LOWE.
